Attorney.

UNITED STATES PATENT OFFICE.

FRED W. CROCKER, OF LOS ANGELES, CALIFORNIA.

CLASP.

1,392,816.

Specification of Letters Patent.

Patented Oct. 4, 1921.

Application filed July 6, 1920. Serial No. 394,077.

To all whom it may concern:

Be it known that I, FRED W. CROCKER, a citizen of the United States, residing at Los Angeles, in the county of Los Angeles and State of California, have invented new and useful Improvements in Clasps, of which the following is a specification.

This invention relates to a clasp which is especially applicable for use on garment supporters such as sleeve-holders, hose fasteners and the like.

It is the objects of this invention to provide a clasp of the type embodying gripping jaws, having means for locking the jaws in their closed or gripping position to prevent them from becoming accidentally unfastened, but which locking means may be readily manipulated to release the jaws and permit opening thereof.

20 A further object is to provide a device of the above character which is simple in construction, reliable, durable, and efficient.

Other objects will appear hereinafter.

The invention is illustrated in the accompanying drawings, in which:

Figure 1 is a perspective view of the clasp showing one of its jaws in an open position and the other jaw in a closed position.

Fig. 2 is a view in longitudinal section of 30 a jaw as seen in its open position.

Fig. 3 is a longitudinal section of a jaw showing it in its locked closed position.

Fig. 4 is a view in transverse section as seen on the line 4—4 of Fig. 3.

35 In carrying out my invention I employ a pair of clasp members or jaws 5 and 6 of corresponding construction, each of which embodies a fixed jaw member 7 and a pivoted jaw member 8; the fixed jaw members 40 of the clasp being connected together by links 9 or other suitable flexible connections. Each of the jaw members 7 and 8 are preferably formed of sheet metal and have a substantially rectangular inner end portion 45 and an outwardly flared outer end portion terminating on an arc, and also have an inwardly extending serrated end flanges 10 forming gripping teeth on the outer end of the jaw members adapted to intermesh with each other when the jaw members are closed.

50 The inner end portion of each jaw member 7 and 8 is formed with inturned side flanges 11 and 12 constituting lugs and arranged with the flanges 12 of the jaw member 8 extending between the flanges 11 and projecting alongside thereof; the flanges 11 and 12

being pivotally connected together by a pivot pin 14 to form a hinged joint between the jaw members whereby the serrated outer end of the member 8 may be moved toward 60 or away from the serrated outer end of the member 7. Mounted on the underside of the fixed jaw member to slide lengthwise of the flange 11 is a slide bar 15 having a tapered or wedge shaped end portion 16 adapted to 65 pass over and engage an upturned end flange 17 on the inner end of the pivoted jaw member in such manner as to clamp the latter in its closed position, as shown in Fig. 3. A slot 18 is formed in the fixed jaw member 70 above the slide bar 15 and the latter has its outer end upturned to form a finger piece 19 which projects through the slot and overhangs the edges thereof to effect a slidable connection between the bar and the sides of 75 the slots, whereby the slide bar is held in place on the fixed jaw member; the bar being held against turning on the latter by the side flange 11.

In the operation of the invention, when it is 80 desired to open the jaw members 7 and 8 the slide bar 15 is moved to a retracted position to dispose the tapered end clear of the upturned end of the pivoted jaw members, as shown in Fig. 2, thus disengaging the pivoted jaw 85 member and permitting it to swing in its open position; the upper edge of the flange 17 entering a slot 20 formed in the fixed jaw member to permit sufficient opening movement of the jaw, which movement is limited 90 by the flange 17 abutting against the edge of the slot. When it is desired to clamp the jaw members of the clasp in their closed position the jaw member 8 is swung toward the jaw member 7 and the slide bar 15 is advanced to extend between the flange 17 and the slot 20, as shown in Fig. 3, thereby holding the pivoted jaw against movement relative to the fixed jaw.

While I have shown and described a specific embodiment of my invention, I do not limit myself to the exact details of construction set forth, but may employ such modifications and changes as occasion may require and as come within the scope of the 100 appended claims.

I claim:

1. In a clasp, a fixed jaw member, a slide bar guided thereon having a tapered end portion, a movable jaw member pivoted on 110 said fixed jaw member having an end flange adjacent its pivot turned toward the fixed

jaw member, the tapered end portion of said slide bar being adapted to be moved in and out of a position between the end of said flange and the fixed jaw member.

5. 2. In a clasp, a fixed jaw member, a movable jaw member pivoted thereon, an upturned flange on said movable jaw member adjacent its pivot, a slide bar on the under-side of said fixed jaw member adapted to be interposed between the upturned flange on the movable jaw member and the fixed jaw member for locking the jaw member against movement relative to each other in a closed position, and a thumb piece on said slide bar

10 extending through said fixed jaw member.

15

3. In a clasp, a fixed jaw member, a movable jaw member pivoted thereon, an upturned flange on said movable jaw member adjacent its pivot, a slide bar on the under-side of said fixed jaw member adapted to be 20 interposed between the upturned flange on the movable jaw member and the fixed jaw member for locking the jaw members against movement relative to each other, and a thumb piece on said slide bar extending through said fixed jaw member having slide-able engagement with the side walls of a slot formed in the fixed jaw member to afford a mounting for said slide bar.

FRED W. CROCKER.
